UNITED STATES PATENT OFFICE.

OSCAR E. McCASKILL, OF FORT WORTH, TEXAS.

PUMPING MECHANISM FOR WINDMILLS.

Application filed September 2, 1926. Serial No. 133,242.

My invention relates to pumping mechanism and more particularly in windmill construction to means for guiding and lubricating the crosshead and co-operating parts; and the object is to provide a more simple means for guiding the crosshead and to provide a more simple means for keeping the working parts lubricated and to eliminate several cumbersome and expensive guiding parts. Other objects and advantages will be fully explained in the following description and the invention will be more particularly pointed out in the claims.

Reference is had to the accompanying drawings which form a part of this application.

Fig. 1 is a broken view, being a vertical cross-section of the gear casings and connections.

Fig. 2 is a similar view on a smaller scale, showing a variation of the crosshead which permits the bracing of the guide tube from the hood.

Fig. 3 is a vertical longitudinal section of the gear casing and connections.

Fig. 4 illustrates a variation in the cross-head connection with the upper end of the guiding means.

Fig. 5 is a horizontal section, taken on the line 5—5 of Fig. 4.

Fig. 6 is a detail view of the upper end of the cross-head and guide tube.

Similar characters of reference are used to indicate the same parts throughout the several views.

The drawings show the operating parts of the windmill and pumping mechanism and the gear casing and supports. The casing 1 has extensions 2 and 3 which inclose the gearing. Bearing members 4 and 5 for the windwheel shaft 6 are bolted to the casing 1. These bearing members carry enough lubricant to keep the parts lubricated. Oil or other lubricant is to be placed in the casing and filled up to the windwheel shaft 6. Pinions 7 are rigid with the shaft 6 and mesh with and drive cog wheels 8. The gear wheels 8 are rigid with a shaft 9 which is journaled in bearings 10. The windwheel 50 drives the shaft 6 which drives the pinions 7 which drive the cog wheels 8. The cog wheels 8 actuate the pitman bars 11 which are pivotally connected to the wrist pins 12 which are rigid with the wheels 8. The pitman bars 11 are pivotally connected to the crosshead 13 by pivot bolts 14. The

crosshead 13 has lateral extensions at the lower end and these extensions are slotted above the pivot pin holes. After the pivot pins are inserted in their holes or sockets, 60 the parts opposite the sides of the slots are drawn towards each other by bolts 15 to clamp the pivot pins 14 against turning. The crosshead 13 is a tubular structure provided with the integral lateral extensions for 65 connection with the pitman bars and the crosshead moves vertically on the outside of the tubular guide 16. The tube 16 serves as a guide for the cross-head 13 and holds the lubricant in the casing 1. This tube 16 70 is rigid with casing 1 and forms a passage way for the piston rod 17 and prevents any lubricant from coming in contact with the piston rod 17 which moves vertically within the tube 16. The tube 16 is extended further up than the high point of the stroke of the crosshead 13 so that it will form a guide for the crosshead. See Figs. 4 to 6 inclusive.

One method of attaching the piston 17 to the crosshead 13 is shown in Fig. 1. The 80 cross-head has an annular interior shoulder 18 and the piston rod 17 has a head 19. A cap 20 is screwed into the crosshead 13 and a set screw 21 is screwed through the cap 20 and bears slightly on the head 19 of piston rod 17 and holds the head loosely against the shoulder 18. This permits a swivel of 85 the piston rod 17 at its upper end.

Another method of attaching the piston rod 17 to the cross-head is shown in Fig. 2. 90 The piston rod 17 is rigidly connected to the crosshead 13 by screwing the end of the piston through the top of the crosshead and securing the piston rod to the crosshead by a nut 22. A head 23 is attached to the casing 1 and the guide 16 is braced by bolts 95 24 projected through slots 25 in the cross-head 13 and bearing against the guide tube 16. The slots 25 are long enough to permit the full stroke of the cross-head 13.

Another method of attaching the piston rod 17 to the crosshead 13 is shown in Fig. 4 and in Fig. 6. The piston rod has a head 105 26 which fits in a slot in the top of the crosshead. A cap 27 is screwed down on the crosshead 13 to hold the piston rod 17 rigidly to the crosshead. This method permits the bracing of the guide 16 by means of a cap 28 and brace rod 29 which may be attached to the casing 1. In this construction the guide tube 16 is slotted to accommodate the T-head 26 on piston rod 17 and

long enough to permit full strokes of the crosshead 13.

Various other changes in the construction, proportion and arrangement of the several parts may be made without departing from my invention. One of the advantages of this invention is that a single guide rod, as above shown, provides a more flexible mechanism when used in connection with differential gears and suitable self-aligning pitman bearings because it permits a rocking motion of such gears and bearings about the guide rod for causing both gears to be driven by pinions at all times thereby overcoming the bad effects of unevenly divided teeth in either gears or pinions.

The oil level stands in casing 1 approximately even with the bottom of shaft 6. The bottom step 29 of the crosshead 13 dips into the oil on the downstroke and on the upstroke, the bottom step 29 of the crosshead 13 carries oil above the position of the upper step 30 at its down stroke. As the upper stroke is taking place, the oil is wiped from the outside of the tube 16 and the oil flows through a slot in the crosshead 13 on top of pin 14 and on into the upper pitman bearing.

What I claim, is,—

- 30 1. In a windmill mechanism provided with a casing and a vertically movable piston rod; a crosshead for said piston rod, a tubular guide for said crosshead rigid with said casing and having a liquid tight connection therewith and forming a passage way for the piston rod and forming a guide for a crosshead and preventing lubricating material from touching said piston rod, and means for lubricating said crosshead.
- 35 2. In a windmill pumping mechanism provided with a casing and a vertically moving piston rod; a crosshead for said piston

rod, a tubular guide for said crosshead rigid with said casing and forming a passage way for said piston rod and preventing lubricant 45 from touching said piston rod and forming a guide for a crosshead, and means for lubricating said crosshead.

3. In a windmill pumping mechanism provided with a casing and a vertically moving piston rod and a crosshead driving said piston; a tubular guide rigid with and having a liquid tight connection with said casing and forming a passage way for said piston rod running within said guide and forming a guide for said crosshead running on the outside of said guide and protecting said piston rod from lubricant, and means for lubricating said crosshead.

4. In a windmill pumping mechanism 60 provided with a casing and a vertically moving piston rod and a crosshead driving said piston; a tubular guide rigid with said casing and forming a liquid tight connection therewith, said crosshead surrounding and 65 vertically moving on the outside of said guide, means for lubricating said crosshead, and means operatively connecting said piston rod and cross-head.

5. In a windmill pumping mechanism 70 provided with a lubricant containing casing and a vertically moving piston rod and a crosshead; a tubular guide rigid with said casing and forming a passage way for said piston rod and preventing lubricant from 75 coming in contact with said piston rod, and forming a guide for said crosshead moving vertically on the outside of said guide, means for lubricating said crosshead, and means for operatively connecting said piston rod 80 and said crosshead.

In testimony whereof, I set my hand, this 18th day of August, 1926.

OSCAR E. McCASKILL.
